UNITED STATES PATENT OFFICE.

LEON E. LA BOMBARD, OF WEST NEWTON, AND MELVIN H. SIDEBOOTHAM, OF NEWTONVILLE, MASSACHUSETTS, ASSIGNORS TO SPECIALTY AUTOMATIC MACHINE COMPANY, OF CHELSEA, MASSACHUSETTS, A CORPORATION OF MASSACHUSETTS.

PAPER PAIL AND HANDLE THEREFOR.

Application filed February 19, 1927. Serial No. 169,606.

This invention relates to containers, especially paper receptacles, for food articles such as salads, oysters, baked beans, etc. For such purposes it is preferable that the 5 receptacles shall be seamless in the sense that the paper material is continuous; that is, having no slits or crevices requiring to be protected against leakage by overlapping flap portions. It is also preferable to avoid 10 the use of any adhesive to retain the paper blank in folded or set up condition.

One of the objects of the present invention is to reduce the cost of the receptacles by so forming the continuous or unslotted blanks 15 which are to be folded to condition for use that there is an important saving in the area of the material required to make receptacles of given sizes or capacities, such as half-pints, pints, or quarts.

20 Another object is to provide handles for the receptacles at very low cost, said handles being preferably of a flat character to bear printed advertising matter, and which handles can be easily connected to the receptacles after the latter have been filled and their tops or lids closed.

Another object is to provide attachments for the receptacles which serve the double purpose of holding the tops of the receptacles closed and as handles for carrying 30 the filled receptacles.

With the above and other objects in view, the invention consists in the construction and combination of parts substantially as 35 hereinafter described and claimed.

Of the accompanying drawings:—

Figure 1 is a plan view of two blanks, illustrating how they are cut with but very little waste of material.

40 Figure 2 is a perspective view of a closed receptacle and a handle therefor, the receptacle and handle being separated.

Figure 3 is a similar view with the handle applied to the receptacle.

45 Figures 4 and 5 are views similar to Figures 2 and 3, but illustrating another form of handle.

Figures 6 and 7 are views similar to Figures 2 and 3, but illustrating another form 50 of handle.

Figures 8 and 9 are views similar to Fig-

ures 2 and 3, but illustrating still another form of handle.

Similar reference characters indicate similar parts or features in all of the views. 55 It is to be understood that, in practice, the paper material is not as thick as illustrated in the drawings.

Referring first to Figure 1, each blank is rectangular in form with right-angular 60 corner edges and preferably, although not necessarily, with all four edges of equal length. All of said edges are straight from one right-angular corner to another excepting for two angular notches or recesses α formed in each edge which notches are provided, and so shaped, that when a blank is converted to set up condition there will be no edge portions projecting outside of or beyond the top portions of the receptacle. 70 Owing to the formation of the blanks as illustrated by the two blanks shown in Figure 1, said blanks are readily cut from sheet or web material with absolutely no waste excepting the small somewhat diamond-shaped pieces that are cut out, one-half from the margin of one straight-edged blank and the other half from the margin of the next straight-edged blank, as illustrated at the junction of the two blanks of Figure 1. In 75 practice this amount of waste is only about seven per cent of the material.

Each blank is creased to provide a bottom section a , four side wall sections b each having a top-closing flap d , and with four 80 pairs of V-shaped sections c between and integral with the sections b , said sections c alternating with the sections b . Each complete blank is continuous throughout its area; that is, it is free from slits through 85 which leakage might occur when it is folded or set up to receptacle condition. The creasing may be effected, and preferably is, by the same machine as that which cuts or dies out the blanks. It may, however, be 90 done by a separate machine.

The sections of the blanks are so relatively 95 shaped and proportioned that when a blank is folded or set up as illustrated in several figures of the drawings, the doubled sections c will meet at the upper ends of their mid-folds without overlapping. This meet-

- ing without overlapping is important in order to provide for joining their tips as presently described and to facilitate engagement of the handles as will be described.
- 5 For convenient brevity of description the sections *c c* will be referred to as folded wing sections.
- When the blank is converted to set up condition, the upper tips of said wing section which meet in one plane are secured together and to the side walls *b b* by staple fastening *e e*, this being effected at two opposite sides of the receptacle close to the top thereof. This structure provides what 10 may be conveniently described as thin vertical pockets between the outer surfaces of two of the walls *b* and the inner faces of the overlying wing sections *c*, close to the tops of the latter, for interengagement therewith 15 of the handle members presently described. Such interengagement could not be effected at a high enough point to avoid risk of tilting the receptacle if the acute-angled portions of the wings *c* overlapped.
- 20 Referring now to Figures 2 and 3, the handle comprises a flat strip *f*, preferably of strong paper such as kraft paper, having notches in the edges at each end to form prongs *f'*, said prongs projecting toward 25 the mid-length of the strip. Said strip, in practice, usually bears printed matter applied thereto while the strip is flat from end to end, such printing being easily effected by the same machine as that which 30 dies out the strip with its prongs. When a receptacle has been filled and the top flaps *d* closed down, the prongs *f'* at each end of the handle strip are slipped up into the 35 pockets behind the upper corners of the folded and permanently secured wings *c* as illustrated by Figure 3, and are held there by the frictional grip of the surfaces between which said prongs have been slipped. When the receptacle is to be emptied, a 40 reverse movement of the ends of the handle will completely disconnect it. Or, if desired, the handle can be torn away, being of inexpensive paper and not intended for another use.
- 45 The receptacle may have one of its top closing flaps provided with a slot *g* and the opposite top flap provided with a bendable metal strip *h* to be interengaged with said slot *g* to hold the top flaps closed. This last- 50 mentioned feature is not important however, since the handle itself may have a member which holds the top flaps closed, as illustrated by Figures 4 to 9 inclusive. In said Figures 4 to 9 the receptacle itself is the 55 same as has been described in connection with Figures 1, 2 and 3, but omitting the slot *g* and metal strip or tongue *h*.
- 60 Figures 4 and 5 illustrate a handle comprising a strip *i* having edge slits near each 65 end providing laterally projecting prongs

i', preferably with a strip of bendable metal *i''* enclosed in the paper and extending from side to side. The strip *i* has apertured wings *i³* which, when turned up as illustrated by Figure 5, provide a hand grip. 70 The total length of the strip *i* is such that the prongs *i'* at its ends are at the right distance apart to cause said strip, when its end prongs are slipped into the pockets under the wing sections *c*, to cross the top flaps *d* snugly and 75 hold them down.

In Figures 6 and 7 the structure is substantially the same as in Figures 4 and 5, where the same reference characters are employed. The difference is that the strip *i*, 80 instead of having laterally projecting prongs, has at each end a tapered prong *k*, and the strip and its prongs have a strip *k'* of bendable metal enclosed therein or otherwise carried thereby, so that when the 85 prongs are slipped down behind the staples *e* and then bent to hook form as shown in Figures 7, the said strip *i* holds the flaps *d* closed and the wings *i³* can be employed as a hand grip. 90

Figures 8 and 9 illustrate a paper strip folded or doubled at a point a little to one side of its mid-length to provide a lower member *l* and an upper member *l'*. Near the fold said strip is notched in its sides to 95 provide prongs *l''* all four of which prongs are to be engaged with the pocket in one of the sides of the receptacle. At the other end of the member *l* there are two lateral lips *l³ l⁴*, and the adjacent end of the member *l'* is notched to provide prongs *l⁵*. When this form of attachment is to be applied to a receptacle, the prongs *l''* are first slipped into engagement with the pocket behind the 100 folded wings at one side of the receptacle, then the free end of the strip member *l* is slipped into engagement with the opposite pocket, its lip *l³* so engaging the fold of one of the wings *c* that the member *l* crosses the top flaps *d* snugly and holds said flaps down. 105 Then the free end of the strip member *l'* is slipped into engagement with the same pocket over the end of the member *l*, and the lower lip *l⁴* of the member *l* is bent out past the extreme edge of the member *l'*, at its 110 end, thereby locking the handle member *l'* against displacement, as illustrated in Figure 9. 115

Each form of handle illustrated is economically made by a well-known dieing out 120 method, and can easily be printed at the same time, the cutting and printing being capable of being effected at the rate of approximately 500 a minute. Since the handles are made in flat condition, and when in use 125 exhibit transversely flat surfaces, excellent surfaces are provided not only for effecting printing thereon but also for presenting printed matter to view.

When a receptacle is to be emptied of its 130

contents, no time need be wasted by attempting any careful removal of the handle in order to lift the flaps *d*. A pull on the handle will readily tear it away without in any

5 way affecting the receptacle.

Referring again to Figures 2 and 3, it will be seen that the flap *d* which is provided with the metal strip *h* is so formed that its tip is tapered as at *d'*, said tapered tip, at 10 its widest portion, practically equalling the length of the slot *g* so that, when the said tip *d'* is pushed fully into the slot and bent back as shown in Figure 3, there can be no relative lateral movement of the flaps which 15 have the said slot and tapered tip. This steadies the box and especially prevents it from flexing to askew condition. Of course the boxes illustrated by Figures 4 to 9 inclusive may have the same structure of slot 20 and tapered tip to perform the above-described functions, illustration thereof being omitted from said Figures 4 to 9, to avoid an unnecessary complication of the figures.

25 It is important that the metal strip *h* shall be affixed to the surface of the flap *d* which is uppermost when said flap is first folded down as illustrated by Figure 2. This is to avoid injury to the fingers of the person 30 who then bends the tip and strip to the condition illustrated by Figure 3. When so bent, a user's fingers contact only with the surface of the paper tip *d'*, or its edges, which prevent any contact with any portion 35 of the metal strip *h*. If such metal strip were to be exposed to such contact, the edges or other rough or sharp portions of the strip would be liable to cause injury. Furthermore, when the pail is being carried, the 40 paper material is then so covering the metal strip as to protect the carrier's knuckles from any injury due to contact with the top of the box.

Having now described our invention, we 45 claim:—

1. A paper blank for a seamless receptacle, said blank being rectangular in form with right-angular corner edges and continuous throughout its area and having a pair of 50 angular notches in each edge, each edge being straight from corner to corner excepting for said notches, said blank being creased to provide a bottom section, four wall sections having top-closing flaps, and angular 55 creased sections alternating with the wall sections.

2. A paper receptacle free from slits, consisting of a rectangular sheet folded to pro-

vide a bottom and four walls with top-closing flaps, two of the walls having folded 60 wing portions superimposed thereon, the folds of said wing portions converging upwardly and meeting without overlapping at a point close to the top of the receptacle, the tips of said folded wing portions being 65 secured together and to the side walls to provide effective pockets for engagement of a handle.

3. The combination with a paper receptacle having opposite walls composed of 70 over-folded portions providing pockets close to the tops of said walls, of a flat paper handle having end portions removably engaging said pockets.

4. The combination with a paper receptacle having opposite walls composed of over-folded portions providing pockets close to the tops of said walls, of a handle having 75 prongs to removably engage said pockets.

5. The combination with a paper receptacle having opposite walls composed of over-folded portions providing pockets close to the tops of said walls, of a paper handle having prongs to removably engage said 80 pockets, said handle being normally flat when 85 disengaged from the receptacle.

6. The combination with a receptacle having top-closing members and having pockets close to the tops thereof in two of its walls, of a flexible strip having means to engage 90 said pockets, said engaging means being spaced to cause the strip to hold the top members of the receptacle closed when engaged with said wall pockets.

7. The combination with a receptacle 95 having top-closing members and having pockets in two of its walls, of a double flexible strip having means to engage said wall pockets, one member of said strip having its pocket-engaging means spaced to cause 100 said member to hold the top members of the receptacle closed when engaged with said wall pockets, the other member of said strip having its pocket-engaging means spaced 105 farther apart to enable it to be employed as a handle.

8. A normally flat paper handle for a receptacle, said handle comprising one portion having integral prong members to engage with portions of the receptacle and having 110 another portion integral therewith and formed to provide a hand grip portion.

In testimony whereof we have affixed our signatures.

LEON E. LA BOMBARD.

MELVIN H. SIDEBOOTHAM.
